US0D1096587S

(12) **United States Design Patent** (10) **Patent No.:** **US D1,096,587 S**
(45) **Date of Patent:** **** Oct. 7, 2025**

(54) **FENCE**

(71) Applicant: **GUANGZHOU ISSYZONE TECHNOLOGY CO., LIMITED**,
Guangzhou (CN)

(72) Inventors: **Zhuo Jia**, Guangzhou (CN); **Taiping Yang**, Shenzhen (CN)

(73) Assignee: **GUANGZHOU ISSYZONE TECHNOLOGY CO., LIMITED**,
Guangzhou (CN)

(**) Term: **15 Years**

(21) Appl. No.: **29/906,810**

(22) Filed: **Nov. 10, 2023**

(51) LOC (15) Cl. **12-16**

(52) U.S. Cl.

USPC **D12/414; D12/414.1**

(57) **CLAIM**

The ornamental design for a fence, as shown and described.

DESCRIPTION

FIG. 1 is a rear, right and top perspective view of a fence, showing our new design;

FIG. 2 is a front, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 of FIG. 1 thereof; and,

FIG. 10 is an enlarged view of portion 10 of FIG. 2 thereof. The dot-dash broken lines depict the boundaries of the enlargements that form no part of the claimed design.

1 Claim, 10 Drawing Sheets
